UNITED STATES PATENT OFFICE

93,548

DESIGN FOR A SIGNAL STATION FRONT

Vernon Durbin, Newton, Mass., assignor to The Holtzer-Cabot Electric Company, Roxbury, Mass., a corporation of Massachusetts

Application February 12, 1934, Serial No. 50,697

Term of patent 14 years

To all whom it may concern:

Be it known that I, VERNON DURBIN, a citizen of the United States, residing at Newton, in the county of Middlesex and Commonwealth of Massachusetts, have invented a certain new, original, and ornamental Design for Signal Station Fronts, of which the following is a specification, reference being had to the accompanying drawing, forming part hereof.

The figure is an elevation of the door and front plate or escutcheon of a signal station for fire alarm purposes, showing my new design.

The signal station front is comparatively thin and substantially flat; the moldings being of different levels than the stippled portions.

I claim:

The ornamental design for a front for a signal station, substantially as shown and described.

In witness whereof, I hereunto subscribe my name this 10th day of February, 1934.

VERNON DURBIN.
